UNITED STATES PATENT OFFICE.

CHARLES W. CARR, ROBERT J. DIXON, AND PETER W. CONOVER, OF OGDEN, UTAH.

ELEVATOR-DOOR LOCK.

Application filed March 2, 1922. Serial No. 540,425.

To all whom it may concern:

Be it known that we, CHARLES W. CARR, ROBERT J. DIXON, and PETER W. CONOVER, citizens of the United States, residing at Ogden, in the county of Weber and State of Utah, have invented certain new and useful Improvements in Elevator-Door Locks, of which the following is a specification.

This invention has reference to elevator door locks of extremely simple construction and not liable to get out of order and which may be safe and reliable in operation as well as requiring the completion of an electric circuit before the elevator can be started.

15 In accordance with the invention, the lock includes two associated casings, one of which operates to close an electric circuit and the other of which operates as a catch member holding the lock positively closed until the parts are operated to effect the unlocking of the device.

One of the lock members is provided with circuit terminals and may be made fast to a fixed part of the door carrying the lock, 25 while the other latch member may be made fast to a catch member, which on the closing of the door completes the circuit and renders it possible to start the elevator in operation, which starting of the elevator cannot be accomplished until the circuit is completed.

One of the companion lock casings is provided with a gravity catch and the other lock casing is provided with a keeper which under certain circumstances may be engaged by the catch and so hold the two lock members 35 against escape until desired.

The catch is responsive to hand movement and is adapted to operate a contact member completing an electric circuit within the casing containing the contact member which in turn is responsive to the impact of the contact member so as to cause the locking of the contact member in the closing position thus establishing an electric circuit.

45 The invention will be best understood from a consideration of the following detailed description taken in connection with the accompanying drawings forming part of this specification with the understanding however that the invention is not confined to any strict conformity to the showing of the drawings, but may be changed and modified so long as such changes and modifications mark no material departure from the salient 50 features of the invention as expressed in the appended claims.

In the drawings:

Figure 1 is an elevation, partly in section, showing the elevator lock in the closed position.

Fig. 2 is an elevation of the lock with the latter disengaged or in the open position. Referring to the drawings, there are shown two lock casings A and B respectively, and these casings may be of similar, although not necessarily the same size and correspond to lock casings such as are usually employed in elevator locks.

The lock casings are provided with marginal flanges 1 and 2 adapted to receive cover members 3, 4. Each lock flange is provided with a slot or cutout 5 and 6, respectively, which slots are adapted to match one another when the casings are in the locking position. The flange 1 of the lock member 75 A is provided with a passage 7 for accommodating electric wires or conductors 8, 9, which may be assumed as coming from any suitable source of electric current and as they do not differ from other electric currents, need not be particularly described.

Mounted within the casing A and inside of the flange 1, are clips 10 suitably spaced apart and adapted to carry between them a block 11, which may be formed of insulating material.

Considering the block 11 as formed of insulating material, it has made fast to it a through pin 12 held to the block by nuts 13, so as to firmly clamp the block and pin in position.

The nuts 13 are designed to secure terminal 14 to a pin 12 and this terminal is in turn made fast to the conductor 8, one terminates close to the slot or passage 5 in a 95 pair of fingers or flanges 15 carrying between them a corresponding insulating block 16 also carried by a clip 17 so that the block may be held firmly and yet removably in the casing A.

Traversing the block 16 is a conducting pin 18 held to the block by clamp nuts 19 similar to the nuts 13.

The clamp nuts 19 hold a contact terminal 20 to the pin 18 and this contact terminal 20 is made fast to the electric conductor 9, both of the conductors 8 and 9 reaching the exterior of the casing through the passage 7 in the flange 1.

Located in the lock casing A is a rock arm 110 22, which for the sake of lightness may be made of vulcanized fiber or some other such

material and this arm is lined or flanked on opposite faces with strips 23 secured to the arm by bolts 24.

Fast to opposite sides of the arm 22 are 5 conducting fingers 25, 26, respectively, and these fingers are coupled together through the bolts.

In this manner the two conductors 8 and 9 are electrically connected by the pins 14, 10 finger 25, bolts 24, finger 26 and pin 18 to said electric conductors 8 and 9.

Within the casing B there is an irregularly shaped arm 27 constituting a catch member and so shaped as to be heavier at 15 one end than at the other so as to overbalance about a pivot pin 28 with a catch end or hook 29 normally extending through the passage 6 and capable of being projected through the passage 5 of the casing A.

When the lock is mounted upon an elevator door, the operation thereof may be described as follows.

When the elevator lock, constructed in 25 accordance with the invention, is installed on the elevator door and casing, the member A constitutes the stationary casing and is carried by the stationary member, while the elevator door, which is usually a sliding 30 member is carried by the elevator cage.

The lock casing A carries the electric conductors 8 and 9 which therefore need no adjustment. The conductor 8 is electrically connected to the insulated pin 14, while the 35 electric conductor 9 is electrically connected to the insulated pin 18.

So long as the lock casings A and B are not in engagement, the overbalanced contact arm 22 rocks on an arm 30, on which 40 it is supported, and drops to a supporting pin 31 in the casing A thus carrying the contact fingers 25 and 26 out of engagement with the pins 14 and 18. This occurs when the catch 27 has moved from engagement 45 with a keeper 32 within the casing A.

When the catch 29 is manipulated by the hand of the operator, it may be lifted out of the path of the keeper and the elevator door may be pulled away from the casing 50 A thus releasing the arm 22 and permitting the arm 27 to be withdrawn from the keeper 32.

When the catch 29 has entered the casing A, its natural tendency is to gravitate behind the catch 32 and the arm 22, being 55 an overbalanced arm, will drop down upon the shorter arm of the arms 22 thus causing the longer end of the arm to lift with the result that the fingers 25 and 26 are moved 60 into engagement with the projecting ends of the pins 14 and 18 causing the fingers carried by the arm 22 to make contact with these pins and thus establish the circuit controlled thereby. When the arm 22 is rocked 65 to an approximately horizontal position,

which it does when engaged by the catch 29 with the door of the elevator moved from within the casing A, the circuit through the conductors 8 and 9 is broken and the lock is no longer affected by the catch 29.

The catch 29 is only affected when the catch has entered the casing A and depressed the shorter end of the arm 22, so as to bring the contacts 25 and 26 into electric engagement with the conductors 8 and 9, in which condition they will remain so long as the catch is held in engagement with the arm 22.

When the two members of the elevator lock are caused to approach so that the catch 29 will enter through the openings 5 and 6, the catch 29 being in the meantime manually elevated or even caused to ride onto the top of the arm 22, the electric circuit is completed.

The elevator cannot be started when the door is not shut because the controlling circuit through the conductors 8 and 9 is open or broken and the elevator cannot be again started until the circuit is closed.

What is claimed is:—

1. An elevator door lock comprising two coacting casings, with one casing on the door and the other casing carried by and movable with the elevator, a pivoted, overbalanced catch carried by the first named casing and movable into the second named casing, and a rockable contact arm carried by the second named casing and having spaced contact terminals in the path of the 100 opposite ends of the rockable contact arm, and bridged by said contact arm when rocked by engagement therewith of the overbalanced catch.

2. An elevator door lock comprising two coacting casings, with one casing on the door and the other casing carried by and movable with the elevator, a pivoted, overbalanced catch carried by the first named casing and movable into the second named casing, and a rockable contact arm carried by the second named casing and having spaced contact terminals in the path of the 105 opposite ends of the rockable contact arm, and bridged by said contact arm when rocked by engagement therewith of the overbalanced catch, each of the spaced contacts being fixedly mounted in the casing appertaining thereto and the rockable contact arm having joined contact fingers at opposite 110 ends movable into engagement with the spaced contacts to bridge them.

3. An elevator door lock comprising two coacting casings, one on the car door and the other carried on and movable with the 115 elevator, a pivoted overbalanced catch carried by the first named casing and movable into the second named casing, a rockable contact arm carried by the first named casing, spaced contact terminals in the path of 120

125

130

135

the opposite ends of the rockable contact arm and bridged by said contact arm when rocked by engagement with the overbalanced catch, contact fingers carried by the rockable arm and electrically connected through said arm to serve as bridging means for an electric circuit when brought into contact with the first named contact, and

an external electric circuit for completion by the electric contacts carried by the rockable arm. 10

In testimony whereof, we affix our signatures hereto.
